BOMB

Emrik Ivar Lindman, Ronninge, Sweden

Application June 11, 1945, Serial No. 598,857
In Sweden October 7, 1940Section 1, Public Law 690, August 8, 1946
Patent expires October 7, 1960

1 Claim. (Cl. 102—7.6)

1

Dummy or practice bombs to be thrown from airplanes are often made of concrete. It has been proposed to weight such bombs with pieces of waste or scrap iron introduced into the concrete in order to give the bomb a sufficient weight. This also renders it possible to adjust the position of the centre of gravity to a certain extent. Among other features, the weight of the bomb and the position of its centre of gravity have a preponderant influence upon the ballistic qualities of the bomb.

These bombs, however, are rather unsatisfactory and they have not the same ballistic qualities as real fighting or explosive bombs. Consequently, these dummy bombs are not suitable for an efficient training of the air-men. In addition, practice bombs heretofore known have very variable ballistic characteristics, though every effort was made at their manufacture to get a uniform product. Consequently, the pattern or spread is bad when such bombs are thrown. One cause of this drawback is that the pieces of scrap iron in the concrete are easily displaced during the solidification of the concrete, thus essentially changing the ballistic characteristics of the practice bomb.

The chief purpose of this invention is to create a practice or indicating bomb which has good, constant and uniform ballistic characteristics but nevertheless is simple and inexpensive to manufacture. In accordance with the invention bombs may be produced which have the prescribed, predetermined ballistic characteristics within very narrow limits, and consequently may be dropped with a minimum of spread, that is with a good pattern. Consequently, the bombing practice may be carried out with the same accuracy as that attained in throwing real fighting bombs, and such practice is far more valuable than the ordinary practice heretofore possible.

It is a well-known matter of fact that fighting bombs of steel are manufactured with very high precision in those ballistic features which are decisive for the path of the bomb through the air. Thus, it is possible to throw such bombs with high accuracy on the target. This could, however, heretofore not be attained, when manufacturing and using practice bombs of concrete. Certainly, efforts were made to give the concrete bomb the same external shape as the corresponding steel bomb, as accurately as possible, but in spite of this the concrete bombs differ very much in other ballistics data from the steel bombs, and also are very variable in such ballistic data. For instance, it was not possible to attain a cor-

2

rect position of the centre of gravity and simultaneously a correct total weight of the bomb, within reasonably narrow limits.

Consequently such practice bombs of concrete were unsatisfactory and not suitable for an efficient training of the air-men. The pattern or spread is bad, when such bombs are thrown. For these reasons, the military supplies authorities found it impossible to prescribe any weight limits, but had to be content with demanding a certain accuracy in the external shape of the bomb. As a matter of fact it was heretofore impossible to attain the desired accuracy in external shape, total weight and position of the centre of gravity. It does not suffice to use exactly the same mould and to pour concrete in it, because even if the components of the concrete are weighed and mixed with high accuracy the composition of the concrete varies much, and consequently concrete bombs moulded in the same mould turn out to be very different. It must be observed that concrete absorbs water, also after it has dried. The decisive ballistic data, such as the position of the center of gravity, the total weight and the external shape, are predetermined with regard to the desired ballistic properties of the steel bomb, taking the properties of the steel into consideration, and it was heretofore impossible to attain the same data in concrete bombs, concrete having quite different properties.

To render concrete bombs really valuable for practice purposes, small bombs should be so accurate that, for instance, their total weight differs at most $\pm 1\%$ from the prescribed average value for the corresponding sharp or fighting bomb of steel. For very big bombs, this tolerated limit may be increased to $\pm 1\frac{1}{2}\%$. Heretofore, it was absolutely impossible to attain values even in the neighbourhood thereof; even steel bombs could not always be manufactured with so high accuracy.

In accordance with my invention, the air bombs may be made of parts with different specific gravity or different weight per unit of volume, which are solidified, dried and weighed. Then such parts are united which together give the desired total weight and also the correct position of the centre of gravity of the bomb. Thus, the whole bomb may be manufactured with the very high accuracy demanded, though it is not possible to manufacture the parts separately with such accuracy. The very fact that a body of concrete cannot be moulded (cast) with a predetermined high accuracy led to the idea that it was impossible to manufacture concrete bombs

with high accuracy in respect of their weight. It should perhaps be mentioned that such accuracy cannot be attained by weighing a predetermined quantity of concrete mass and then introducing said weighed quantity into the same mould. It will be found that nevertheless the finished concrete bombs thus produced vary extensively in their total weight.

The low price and high accuracy of the bombs in accordance with the invention renders it advantageous to use them for practice purposes for "sighting-shots" and other indicating purposes.

Embodiments of bombs in accordance with this invention are shown in the annexed drawing.

Fig. 1 shows a longitudinal section through a (big) bomb in accordance with the invention.

Figs. 2 and 3 show cross sections on the lines II—II and III—III, respectively, in Fig. 1.

Fig. 4 is a longitudinal section through a (small) bomb in accordance with a modified embodiment.

Referring now to Figs. 1-3 of the drawings, a central tube 2, for instance of metal, extends through the whole length of the bomb and, preferably, projects beyond its rear part or tail. In the embodiment shown said tube has a constant cross section, but the cross section may also be varied, preferably in such manner that the tube 2 has a larger cross section towards the tail of the bomb. Around the tube 2 the body proper of the bomb is moulded of concrete. In the embodiment shown, the concrete body is made of two parts 1 and 3 but in certain cases it may be suitable to make the concrete body of another number of parts.

The concrete is composed of a binder, preferably of the hydraulic type, such as cement, together with different mixtures of heavy sand, that is sand having a higher specific gravity than 3.0. In certain cases binders of the asphaltic type or of other types may be used. The heavy sand may consist of ore concentrate or of fine grain ore, preferably iron ore. To it sand of ordinary granite, gneiss or the like, or of concrete clinker, pumice or the like may be admixed. To attain a high weight per unit of volume of the concrete, the sand may be mixed with or entirely consist of granulated iron (so called granule manufactured by granulating pig iron in water) or lead. The word "sand" here has the sense accepted in the concrete technics and consequently indicates particles up to 7 mm. By proportioning the different types of sand in relation to each other and to the binder, it is consequently possible to control the weight per unit of volume to any desired value, within the limits herein concerned.

Preferably, the bomb is cast in a vertical mould, and concrete with the desired weight per unit of volume is poured on different levels, after the preceding pouring has solidified. Thus, it is possible to cause the centre of gravity to assume the desired position, while simultaneously the total weight of the bomb gets the desired value. First the part 1 is cast which has the dominating influence upon the total weight. After this part has solidified, it is weighed, and connected with the part 3. The part 3 may be poured directly upon the part 1 already solidified or the part 3 may first be moulded separately and then secured in its place on the bomb, for instance, by means of cement mortar inserted between the parts 1 and 3 and between the part 3 and the tube 2. If the part 3 is cast directly on the part 1, the quantity of concrete for the part 3 is first

weighed so that it renders the prescribed total weight of the bomb together with the part 1 (after the weight of such metal parts have been deducted which possibly were not weighed together with the part 1). If the part 3 is manufactured separately, series of such parts are generally manufactured, which are weighed after the solidification and then are combined with such parts 1 as will give the desired total weight. It has been found that when bombs are manufactured on a large scale such adjustment of the weight may be made at a low cost.

In one preferred embodiment for small bombs, the nose of the bomb is made of cement, iron ore concentrate and granulated iron in the proportions 1:3:3. About 20-30% of the total weight of the bomb is made of such concrete. The remainder of the part 1, that is about 80-70% by weight of the total weight, is made of concrete consisting only of cement and concentrate of iron ore in the proportions 1:3. Finally, the part 3 is made of concrete having a lower specific gravity.

It is very important that the concrete of every bomb has a homogeneous composition and receives the same treatment. It has been found that the best results are obtained by vibrating the concrete at a high frequency, for instance, in a machine generating the vibrations as elastic oscillations in the material of the vibrating machine proper.

When the tube 2 is inserted into the concrete, it is well anchored therein due to the shrinking of the concrete. If desired, special measures may be taken for anchoring the tube 2 in the concrete.

The bomb shown in Figs. 1-3 is intended to be hung horizontally in the airplane. For this purpose irons 4, 5 are laid in the concrete and bent around the central tube, as shown in Fig. 2. The forward iron 4 is bent in a direction opposite to that of the rear iron 5 so that the bomb has a symmetrical distribution of the weight in relation to its longitudinal axis or a longitudinal plane. In those ends of the irons 4, 5 which extend to the surface of the bomb threaded holes 6 are made for eyes or hooks in which the bomb is hung.

In this embodiment the bomb has tail vanes 7 stayed by an iron ring 8. The vanes have a metal cone 9 enclosing the rear part of the bomb.

In the tube 2 a suitable indicator charge is arranged, such as a smoke forming charge or a light emitting charge or both. For igniting this charge, either by direct shock action or by means of an igniting charge (primer or fuse) and/or an expelling charge (detonator) a firing pin 10 is arranged in the forward portion of the tube 2. This pin is secured to a plate 11 which upon impact against the ground drives the pin 10 inwards and thus ignites the indicator charge. A safety cap 12 may be provided to protect the pin during transportation.

The parts 1 and 3 are often made of concrete having different weights per unit of volume. It has turned out that the slight change of the position of the centre of gravity which is due to the fact that parts 3 of somewhat different weights are used, generally may be neglected without inconvenience. In such cases, in which the allowable limits of the position of the centre of gravity are too small to permit a part 3 to be secured to the tail of the bomb, the final adjustment of the total weight is made in a recess in the part 1a adjacent to the centre of gravity.

of the bomb, as shown in Fig. 4. In such cases only the forward or nose portion of the tube 2 is cast into the concrete, while the tail part of said tube is surrounded by a free channel 31 produced by inserting a second tube from the rear end (from the top of the mould) into the mould around the tube 2. This second tube is removed, as soon as the concrete has solidified. After the part 1a thus produced has been weighed to find its exact weight, a fixed amount of concrete 30 is introduced through said channel 31 towards the nose of the bomb, that is towards the centre of gravity, and this addition is left to solidify. The rear end of the channel around the tube 2 may then be sealed in any suitable manner, as shown at 32.

Also in Fig. 4 the practice or indicator bomb 1 is made of concrete with such additions (such sand) that the bomb gets substantially the same ballistic characteristics as a fighting bomb of the same size. The bomb has tail vanes 7. The tube 2 has a shoulder or abutment which in the embodiment shown consists of a screw 17 screwed through the wall of the tube. From the nose of the bomb a tube 18 is pushed into the tube 2. The rear end of the tube 18 abuts against the screw 17 and the tube 18 is filled with an explosive, preferably black powder, though in some cases nitrous powder may also be used. In the upper or nose end of the tube 18 a primer 19 is arranged.

The striking plate 11 has an eye 20 for hanging the bomb vertically in the airplane.

The plate 11 is normally locked by a safety device 33, which is removed when the bomb is thrown from the airplane in well-known manner.

Below (behind) the powder-filled tube 18 a tube 27 is placed which, for instance, contains a smoke-forming substance or a light-emitting charge, which is expelled (or ignited and expelled) by the explosive in the tube 18 when the bomb strikes the ground. The tube 27 is secured by means of a split pin 28, a resilient hook or the like.

Because the weight of a body of concrete varies with its percentage of humidity, it is suitable to coat the finished bombs with a non-adhesive, water-repulsing coating, such as paraffin wax. It is suitable to use a solution of solid paraffin in a liquid hydrocarbon, such as benzene, which evaporates after the coating process. Bombs thus coated have a constant weight even if they are stored or subjected to rain or the like.

It has turned out that bombs in accordance with this invention may be manufactured with the same accuracy as fighting bombs, as far as the ballistic characteristics are concerned. Consequently the practice or indicator bombs in accordance with this invention may be dropped with at least the same accuracy as fighting bombs in spite of the fact that the cost of manufacture of the bombs in accordance with this invention is only a small fraction of the costs of corresponding fighting bombs. An accuracy of $\pm 1\%$ in the total weight and other ballistic elements may easily be attained by use of this invention.

Some of the features illustrated and described herein are also illustrated and described but not claimed in my copending U. S. patent applications Serial No. 417,728, filed November 11, 1941, now Patent No. 2,456,289 and No. 598,856, now abandoned, filed simultaneously with my present application.

What I claim is:

A method of manufacturing air bombs for practice and other purposes, comprising, casting the body of the bomb around a central tube in a vertical mould, while leaving a channel around said tube in the rear part of the bomb, weighing said body with its tube after the concrete has assumed its permanent solidified state, and casting a predetermined quantity by weight of concrete into said channel to render the desired total weight and the desired center of gravity of the bomb.
